COMBINED POSTAL SCALE AND LETTER OPENER

William Stelzer, Summit, N. J.

Application March 26, 1954, Serial No. 29,711

Term of patent 14 years

(Cl. D74—1)

To all whom it may concern:

Be it known that I, William Stelzer, a citizen of the United States, residing at Summit, in the county of Union and State of New Jersey, have invented a new, original, and ornamental Design for a Combined Postal Scale and Letter Opener, of which the following is a specification, reference being had to the accompanying drawing, forming part thereof.

Fig. 1 is a top plan view of a combined postal scale and letter opener, showing my new design;

Fig. 2 is a side elevational view thereof;

Fig. 3 is a bottom plan view;

Fig. 4 is an end elevational view as seen from the left of Fig. 2;

Fig. 5 is a sectional view thereof taken on line 5—5 of Fig. 2; and

Fig. 6 is a sectional view thereof taken on line 6—6 of Fig. 2.

I claim:

The ornamental design for a combined postal scale and letter opener, as shown.
